UNITED STATES PATENT OFFICE.

CLEMENTINA J. M. HAÝNA, OF ST. LOUIS, MISSOURI.

AIR-FEEDING GRATE-BAR.

SPECIFICATION forming part of Letters Patent No. 276,178, dated April 24, 1883.

Application filed December 14, 1882. (No model.)

To all whom it may concern:

Be it known that I, CLEMENTINA J. M. HAÝNA, of St. Louis, Missouri, have made a new and useful Improvement in Air-Feeding Grate-Bars for Preventing Waste in Fuel-Burning Furnaces, of which the following is a full, clear, and exact description, reference being had to the annexed drawings, making part of this specification, in which—

10 Figure 1 is a vertical longitudinal section taken on the line 11 of Fig. 2 of a furnace having the improvement in question; Fig. 2, a vertical transverse section taken on the line 22 of Fig. 1; and Figs. 3 and 4, details upon an enlarged scale, Fig. 3 being a horizontal section taken on the line 33 of Fig. 4, and Fig. 4 a vertical section taken on the line 44 of Fig. 3.

15 The same letters of reference denote the same parts.

20 The present invention is adapted to a great variety of furnaces, including stoves. By means of it the fuel and smoke are thoroughly consumed.

25 A represents a furnace in which the improvement is embodied. It is shown in connection with a steam-boiler, B.

C represents one of the doors of the furnace.

30 The fuel rests upon a series of peculiarly-constructed bars, D D D D' D'. These bars take the place of the ordinary grate-bars in a fuel-burning furnace, extending from the front of the furnace toward the rear end thereof.

35 Each of these bars in cross-section is constructed substantially as shown in Figs. 1, 2, 4—that is, being arched, the arch preferably being quite deep.

40 At the farther end, d, of each of the bars D D D the bar is extended upward in the form of pipes d', Figs. 1, 2, 3, 4. The bars D' D' at each side, respectively, of the furnace are similarly arched underneath, but in place of having a single pipe at the farther end of the bar they have a series of upright tubes, d' d' d', throughout the length of the bar. The bars D D D throughout their length have num-

45 berless perforations, d³, Figs. 1, 3, 4—that is, as many as is practicable for the escape of the air upward from the air-passages d⁵ beneath the bars. The tubular extensions d' d' have at their upper ends, respectively, outlets d⁴, Figs.

50 1, 2, 4. The effect of this construction is to provide air-passages d⁵ d⁵ underneath each bar D D D' D', respectively, wherein air can be

received and heated by means of the burning fuel upon the upper side of the bars. The air also enters the upright passages d' d², and is 55 heated therein. From the passages d⁵ d² d' the heated air escapes through the perforations d' d⁴ upward all over the bottom of the furnace and along the sides and across the rear and a portion of the front end of the furnace, the air 60 being delivered into the furnace-chamber in such quantity and heated to such a degree as to enable the fuel and the smoke to be much more thoroughly consumed than in the ordinary furnace. The bars D' D D D' D' are lat- 65 erally placed closely together and substantially as shown in Fig. 2. The bosses d⁶ d⁶, Figs. 3, 4, serve to keep the bars a slight distance apart, the aim being to separate the bars to that extent only as may be necessitated for 70 the downward passage into the ash-pit of such ashes as may be formed in the furnace. It is not intended to agitate the grate-bars or the fire for the purpose of discharging the ashes forcibly from above the bars, but rather to let 75 the ashes of itself find its way downward into the ash-pit.

It is desirable to have the upright tubes d' d² extended entirely around the furnace-chamber; but where fuel is introduced laterally into 80 the furnace-chamber, as through the furnace-door C in the present case, the upright tubes are necessarily omitted at the points where fuel is introduced.

I do not desire, in the construction of the 85 tubes d' d², to be restricted in horizontal cross-section to any special form. The general shape of the bars D D D D' D', as a set, conforms to the contour of the furnace-chamber in which the bars are placed—that is, for use in a square 90 furnace, such as here shown, the bars are ex- 95 tended forward and backward in the furnace-chamber, and the upright tubes d' d² are in a rectangular form, corresponding to the shape of the furnace-chamber; but in a differently-shaped furnace-chamber—for instance, one of a circular shape—the bars are extended horizontally suitably to meet the walls of the cham- 100 ber, and the passages d' d² then assume a circular form, for the essence of the invention is so constructing the bars D D' D', &c., as to form a series of air-passages horizontally beneath the fire, as seen at d⁵, Figs. 1, 2, 4, and a series of upright air-passages surrounding

the fire, as seen at $d' d^2$, Figs. 1, 2, 3, 4, and so that the heated air shall escape both upward into the burning fuel and also laterally over the fire. By reason of the apertures from the 5 passages $d' d^2$ being at the sides of such passages as shown, the air escaping therefrom into the fire operates to drive the escaping heated current of air and smoke backward into the hotter portion of the fire, serving thereby to 10 consume the smoke.

I claim—

1. A furnace, A, having the bars D' D D D', said bars being arched to form the passages d^3 , perforated at d^3 , provided with the 15 bosses d^6 , and having the perforated tubular extensions $d^2 d'$, as and for the purpose described.
2. A furnace, A, having the bars D' D D D', said bars being arched to form the pas-

15 sages d^5 , perforated at d^3 for the air to pass 20 upward, and provided with the bosses d^6 , as and for the purpose described.

3. A furnace, A, having the bars D' D D D D', said bars being arched to form the air-passages d^5 and perforated at d^3 , and having 25 the perforated tubular extensions $d^2 d'$, as and for the purpose set forth.

4. A furnace, A, the fuel in which is supported upon the bars D' D D D D', said bars being shaped to form the air-passages d^5 , and 30 being perforated at d^3 , as and for the purpose described.

Witness my hand.

CLEMENTINA J. M. HAYNA.
